(57) **CLAIM**

The ornamental design for a fence carrying tool, as shown and described.

DESCRIPTION

FIG. 1 is a perspective view of a fence carrying tool with a handle in a first position and showing my new design.

FIG. 2 is a front elevational view thereof with the handle in the first position, the rear view being a mirror image thereof.

FIG. 3 is a left side elevational view thereof with the handle in the first position.

FIG. 4 is a right side elevational view thereof with handle in the first position.

FIG. 5 is a top plan view thereof with the handle in the first position.

FIG. 6 is a bottom plan view thereof with the handle in the first position.

FIG. 7 is a perspective view of the fence carrying tool with the handle in a second position.

FIG. 8 is a front elevational view thereof with the handle in the second position.

FIG. 9 is a left side elevational view thereof with the handle in the second position, the right side being a mirror image thereof.

FIG. 10 is a rear elevational view thereof with the handle in the second position.

FIG. 11 is a top plan view thereof with the handle in the second position; and,

FIG. 12 is a bottom plan view thereof with the handle in the second position.

1 Claim, 9 Drawing Sheets
